SHUTTLE TIP CONNECTION MEANS

Joseph R. Phaneuf and David A. Tebo,
Southbridge, Mass.

Application June 25, 1947, Serial No. 756,830

11 Claims. (Cl. 139—196)

1

This invention relates to improvements in shuttles for fabric weaving looms and more particularly to novel means of securing protective tips to the ends of such shuttles.

One of the principal objects of the invention is to provide novel means of securing or anchoring metallic tips to the ends of shuttles of the conventional type used with looms for weaving fabrics to more permanently hold said tips.

Another object is to provide improved means of securing metallic tips to the ends of shuttles of the conventional type whereby the force or blow imparted to said ends by the picker stick during the weaving operation tends to increase the anchoring effect rather than causing loosening of the metallic tips.

Another object is to provide novel means of preventing checking or cracking of the ends of the shuttle to which the metallic tips are connected.

Another object is to provide sleeve type connection means, for securing and anchoring metallic tips to the shuttles, so constructed as to prevent loosening of the tips during use and to aid in preventing the ends of the shuttles from checking and cracking.

Another object is to provide anchoring or securing means for the metal ends of shuttles which will aid in preventing said ends from twisting relative to their initial set position of assembly with the respective ends of the shuttles.

Another object is to provide tip securing or anchoring means which may be used as repair units whereby tips of the prior art type which have become loosened may be firmly anchored in place.

Other objects and advantages of the invention will become apparent from the following description taken in connection with the accompanying drawings and it will be apparent that many changes may be made in the details of construction, and arrangement of parts shown and described without departing from the spirit of the invention as expressed in the accompanying claims. We, therefore, do not wish to be limited to the exact details of construction and arrangement of parts shown and described as the preferred forms only have been given by way of illustration.

It has been a conventional practice for a number of years to provide shuttles, of the type employed with machines such as looms for weaving fabrics, with metallic tips for prolonging the life and durability of such shuttles.

One of the major problems, in the past, has

2

been in securing and anchoring the tips in position whereby, during the weaving operation, said tips will not become loosened and displaced or the ends of the shuttle become checked or cracked thereby rendering the shuttles impractical for further use. In several instances in the past, particularly when the metallic tips become loose, great damage has been caused to the warp on the loom. This damage, in most instances, was due to the shuttles being deflected, due to loose tips, from their normal path of travel transversely of the lay of the loom with the result that said shuttle will be directed through the warp and cause the ends to break and to cause considerable time to repair the damage done and also introduced the further element of danger of possible injury to the operator as well as other operating mechanisms of the loom.

One of the prime objects, therefore, of applicants' invention is to overcome the above difficulties through the provision of novel means of anchoring the metallic tips to the ends of the shuttles whereby the said anchoring and retaining of the tips in position tends to increase its holding function during use and further tends to obviate the tendency of the ends of the shuttles to check and crack.

Referring to the drawings:

Fig. I is a perspective view of a conventional type shuttle embodying the invention;

Fig. II is a slightly enlarged exploded sectional view taken as on line 2—2 of Fig. I and showing parts prior to their assembled relation with each other;

Fig. III is a sectional view taken as on line 2—2 of Fig. I showing the parts in assembled relation with each other;

Fig. IV is a bottom plan view of the sleeve type connection means shown in Fig. II;

Fig. V is an end view of the body of the shuttle prior to the assembly of the metallic tip and connecting means therewith;

Fig. VI is a sectional view of a modified form of connecting means;

Fig. VII is a view generally similar to Fig. III illustrating a further modification of the invention; and

Fig. VIII is a sectional view of a further modified form of connecting means.

Referring to the drawings wherein like characters of reference designate like parts throughout the several views, the shuttle embodying the invention, as shown in Fig. I, comprises a main body portion 9 having opposed tapered ends 10

and an intermediate slot 11 extending longitudinally thereof.

Inwardly and adjacent one end of the longitudinal slot 11, there is provided a conventional type clamp 12 for engaging the head 13 of the bobbin 14 for retaining said bobbin in said slot. The end of the filling 15 carried by the bobbin 14 is threaded through the conventional threading means 16 of the bobbin in the end thereof opposed to the clamp means 12.

The tapered end portions 10 of the shuttle, as shown best in Figs. II and III, are provided with metallic tips 17 of a shape which will blend with the outer surfaces of said end portions 10.

The main body portion of the shuttle is formed of a fine-grained wood such as dogwood or persimmon or may be formed partially of plastic or combined wood and plastic or other suitable materials known in the art.

The arrangement embodying the present invention comprises a metallic tip 17 and a tip locking device 21 adapted to be fitted within the tapered end portion 10 of the shuttle. The tip portion 17 comprising a shank 18 is formed with a knurled portion 19 adjacent the base of the tip. The base of the tip 17 is preferably provided with an annular recess 20 surrounding the knurled portion 19 and having its outer contour spaced inwardly from the adjacent contour edge of the base. The tip locking device comprises a pair of concentric sleeve portions 22 and 23 held in fixed spaced relation with each other by an end web or wall 24. The sleeve portion 23 is provided with an inwardly tapering end 25 and sleeve portion 22 is provided with an outwardly tapering end 26, see Fig. II.

The end portion 10 is preferably provided with a substantially flat surface 27 having an annular or circular recess 28 therein adapted to receive the sleeve portion 22. Centrally of the recess 28, there is provided a counterbore 29 for receiving the sleeve portion 23 and a slight counterbore 30 for receiving the webbed end 24. Centrally of the counterbore 29, there is a longitudinal opening 31 adapted to receive the shank 18.

In forming the tip locking device 21, the diameter of the sleeves 22 and 23 as well as the thickness of the walls of said sleeves are carefully controlled as to dimension. The space 32 between the said sleeves is also controlled so that the said parts of said tip locking device will be substantially of uniform size and relation with each other. The diameter of the bore 33 of the inner sleeve 23 is also controlled so as to be of a given amount less than the dimension of the shank portion 18. The outer wall 34 of the recess 28 is preferably of a diameter slightly larger than the outer diameter of the sleeve portion 22 while the inner wall 35 of the recess 28 is of a diameter slightly greater than the diameter of the inner wall 36 of the sleeve portion 22. The depth of the recess 28 is approximately only two-thirds of the length of the sleeve portion 22 whereby, when the said sleeve portion 22 is driven inwardly of the recess 28, the outwardly bevelled end 26 of said sleeve portion will cause the said end to expand inwardly of the solid wood as shown at 37 in Fig. III thereby locking said sleeve inwardly of said tapered end 10. It is to be noted that a slight space 38 remains between the outer wall of the recess and the outer adjacent surface of the sleeve portion 22. This tends to prevent the checking and cracking of the end. While the outer sleeve portion is formed in the above manner, the inner sleeve portion 23 has an outer di-

ameter which is slightly larger than the diameter of the counterbore 29 with the result that the space 32 between said outer and inner sleeve portions 22 and 23 is considerably less than the thickness of the walls of the annular portion 39 lying between the counterbore 29 and the recess 28. The length of the sleeve portion 23 is greater than the depth of the counterbore 29 whereby the end of the sleeve portion 23 will be forced downwardly into the solid side walls of the drilled opening 31 when being driven or pressed within the end of the portion 10. The tapered end 25 functioning cooperatively with the oppositely tapered end 26 will tend to cause the material of the portion 10 to be squeezed or crowded inwardly between the sleeve portions 22 and 23 thereby introducing a firm binding action with the tendency to increase its above function when force is exerted on the end wall 24 of the locking device. After the tip locking device is seated into the end portion 10, as illustrated in Fig. III, the shank 18 together with the knurled portion 19 is then driven or pressed into seated relation with the end 27. The base of the tip 17 is preferably formed slightly concave, as shown at 40 in Fig. III whereby the outer edge thereof will tend to cause the material at the end surface 27 to be crowded slightly inwardly of said cupped surface 40.

The shank, being of a larger diameter than the drill hole 31, will be firmly locked in place and the knurled portion 19 which is of a diameter greater than the diameter of the bore 33 of the inner sleeve portion 23 will cut into the metal and will interlock therewith and thereby prevent rotation of the tip 17 relative to the adjacent end 10 of the shuttle. The tip locking device may be formed of brass, copper, bronze, or steel or any other suitable metal.

It is quite obvious that due to the fact that the space 32 between the outer and inner sleeve portions 22 and 23 is less than the width of the wall 39, that is, when the tip locking device is forced or pressed within the recess 28, there will be an increased tendency for the bevelled edges 25 and 26 to direct all the material of said wall 39 inwardly of the space 32 thereby causing a compression of the material of the portion 39 and a friction binding of the locking device therewith. Simultaneously, to this function, the bevelled end 26 being forced into the solid material of the end portion 10 will cause the adjacent end of the sleeve 22 to spread outwardly, as shown in Fig. III and thereby firmly anchor the locking device within said end 10. When the shank 18 and knurled portion 19 are forced inwardly of the bore 33 and drilled opening 31 to a position wherein the base of the tip 17 is seated against the end surface 27, there will be a further expanding action introduced on the inner sleeve 23 during the cutting of the knurled portion 19 inwardly of the adjacent material of said sleeve thereby further tending to anchor the parts in place. Force applied to tips 17 during use will tend to more firmly anchor the parts in place rather than to cause them to loosen. Due to the fact that the outer wall 34 of the recess 28 is of a diameter larger than the outer diameter of the sleeve portion 22 and that a slight space 38 remains about the assembled parts, the danger of having the end check or crack is greatly reduced. A more positive mechanical bond or anchoring of the tip inwardly of the end 10 is therefore introduced and a much more permanent connection is obtained.

Referring to Fig. VI, there is shown a slight modification of a tip locking device which is generally similar to the tip locking device such as illustrated in Figs. II and III except that it has an integral flange portion 41 extending outwardly of the end wall 42 which supports the inner and outer tubular portions 43 and 44 in desired spaced relation. The device shown in Fig. VI functions in a manner generally similar to that shown in Figs. II and III with the exception that the flange 41 is adapted to overlie the end surface 27 between said end surface and the base of the tip 17 when in use.

In Fig. VII, there is shown a further modification of the invention wherein the central opening, simulating the opening 31, extends entirely through the adjacent end portion 45 of the shuttle. In this instance, the central opening 46 communicates with the longitudinal slot 11 and is increased in diameter inwardly of said end portion by an amount sufficient to permit a cap member 47 to be pressed over the inner end of the shank 48 of the tip 49, which shank 48 and tip 49 are generally similar to the shank 18 and tip 17 shown in Figs. II and III. The connection means is otherwise generally similar to that shown in Figs. II and III with the exception that the side walls of the cap portion 47 are of such diameter as to frictionally interlock with the shank portion 48, that is, the central bore of the cap portion 47 is of a diameter less than the diameter of the shank 48 whereby the parts will frictionally interlock with each other.

In Fig. VIII, there is illustrated a further modification wherein the inner sleeve portion 50 which simulates the inner sleeve 23 is formed to a length considerably greater than the length of the outer sleeve portion 51. It is to be understood that in a tip locking device such as shown in Fig. VIII, the counterbore, such as shown at 29, will be formed of a depth sufficient to accommodate for the inner sleeve portion 50. Each of the tip locking devices shown in Figs. VI and VIII may be used as repair units with shuttles from which the tip portion 17 has been loosened. It is to be understood, of course, that the end 10 of the shuttle would have to be initially prepared in a manner generally similar to that illustrated in Fig. II to receive the tip 17 as well as the integral shank 18 and knurled portion 19 and also the tip locking device.

It is particularly pointed out that the inner sleeve portion 23, as shown in Figs. II and III, is initially formed to a length slightly less than the length of the outer sleeve portion 22 thereby enabling a greater amount of the material of the end portion 10 to be forced inwardly between said inner and outer sleeve portions 22 and 23. The inner surface 52 of the web 24 is adapted to engage the end surface of the annular wall portion 39 and thereby aid in resisting any shock or force inwardly directed against the tip 17.

From the foregoing description, it will be seen that simple, efficient and economical means have been provided for accomplishing all of the objects and advantages of the invention.

Having described our invention, we claim:

1. Means for connecting a protective end member to a shuttle, said means comprising an outer and an inner sleeve portion in substantially concentric relation and joined adjacent one end thereof by an integral web, the opposed ends of said sleeve portions being provided with oppositely angled bevels, with the bevel on the outer sleeve portion extending in an outward direction

and the bevel on the inner sleeve portion extending in an inward direction.

2. Means for connecting a protective end member to a shuttle, said means comprising an outer and an inner sleeve portion in substantially concentric relation and joined adjacent one end thereof by an integral web portion and having oppositely angled bevels adjacent their opposed ends, said inner sleeve portion being of a length less than the outer sleeve portion, with the bevel on the outer sleeve portion extending in an outward direction and the bevel on the inner sleeve portion extending in an inward direction.

3. Means for connecting a protective end member to a shuttle, said means comprising an outer and an inner sleeve portion in substantially concentric relation and joined adjacent one end thereof by an integral web portion, said web having a peripheral flange portion extending outwardly of said outer sleeve portion, said outer sleeve portion having an end surface beveled in an outward direction and said inner sleeve portion having an end surface beveled in an inward direction.

4. In a shuttle the combination of a main member having a recess in one end thereof, said member having a counterbore inwardly of and substantially concentric with said recess and said recess communicating with an opening inwardly of and substantially concentric with said counterbore, a connection member comprising two concentric sleeve portions joined adjacent one end thereof by an integral web, one of said sleeve portions being positioned within the recess and having a length greater than that of the recess and having an outwardly beveled end surface embedded within the material of said main member below said recess and the other of said sleeve portions lying within the counterbore and having an inwardly beveled end extending within the material of the main member at the base of the counterbore and a protective member having an enlarged end portion and a shank portion extending through the central sleeve portion and into the opening concentric with the counterbore.

5. In a shuttle the combination of a main member having a recess in one end thereof, said member having a counterbore inwardly of and substantially concentric with said recess and said recess communicating with an opening inwardly of and substantially concentric with said counterbore, a connection member comprising two concentric sleeve portions joined adjacent one end thereof by an integral web, one of said sleeve portions being positioned within the recess and having a length greater than that of the recess and having an outwardly beveled end surface embedded within the material of said main member below said recess and the other of said sleeve portions lying within the counterbore and having an inwardly beveled end extending within the material of the main member at the base of the counterbore and a protective member having an enlarged end portion and a shank portion engaging and extending through the central sleeve portion and into the opening concentric with the counterbore, said end of the first sleeve portion which is embedded within the material of the main member being flared outwardly.

6. In a shuttle the combination of a main member having a recess in one end thereof said member having a counterbore inwardly of and substantially concentric with said recess and said recess communicating with an opening in-

wardly of and substantially concentric with said counterbore, a connection member comprising two concentric sleeve portions joined adjacent one end thereof by an integral web, one of said sleeve portions being positioned within the recess and having a length greater than that of the recess and having an outwardly beveled end surface embedded within the material of said main member below said recess and the other of said sleeve portions lying within the counterbore and having an inwardly beveled end extending within the material of the main member at the base of the counterbore and a protective member having an enlarged end portion and a shank portion extending through the central sleeve portion and into the opening concentric with the counterbore, the outer wall of said circular recess normally being of a diameter greater than the diameter of that portion of said sleeve portion lying within said recess and having its portion with the beveled end surface which is embedded in the main member flared outwardly.

7. In a shuttle the combination of a main member having a recess in one end thereof, said member having a counterbore inwardly of and substantially concentric with said recess and said recess communicating with an opening inwardly of and substantially concentric with said counterbore, a connection member comprising two concentric sleeve portions joined adjacent one end thereof by an integral web, one of said sleeve portions being positioned within the recess and having a length greater than that of the recess and having an outwardly beveled end surface embedded within the material of said main member below the recess and the other of said sleeve portions lying within the counterbore and having an inwardly beveled end surface and a protective end member having an enlarged tip portion and a shank portion engaging and extending through the central sleeve portion and into the opening concentric with the counterbore, said end portion of the first sleeve portion which is outwardly beveled and embedded within the material of the main member being flared outwardly, the outer wall of said circular recess initially being of a diameter greater than the diameter of the upper portion of the sleeve lying within the said circular recess.

8. In a shuttle the combination of a main member having a recess in one end thereof, said member having a counterbore inwardly of and substantially concentric with said recess and said recess communicating with an opening inwardly of and substantially concentric with said counterbore, a connection member comprising an outer and an inner sleeve portion in substantially concentric relation with each other and joined adjacent one end thereof by an integral web, one of said sleeve portions being positioned within the recess and being of a length greater than the recess and having a flared portion with an outwardly beveled end surface embedded within the material of said main member below the recess and the other of said sleeve portions lying within the counterbore and a protective member having an enlarged head and a shank portion extending through the central sleeve portion and into the opening concentric with the counterbore, the outer wall of said circular recess being of a diameter greater than the diameter of that portion of said outer sleeve portion lying within said circular recess, and said inner sleeve portion being of a diameter

larger than the initial diameter of the counterbore.

9. In a shuttle the combination of a main member having a circular recess in one end thereof, said member having a counterbore inwardly of and substantially concentric with said circular recess and said circular recess communicating with an opening inwardly of and substantially concentric with said counterbore, a connection member comprising two concentric sleeve portions joined adjacent one end thereof by an integral web, one of said sleeve portions being positioned within the circular recess and of a length greater than the recess and having an outwardly flared portion with an end surface beveled in an outward direction and embedded within the material of said main member below said recess and the other of said sleeve portions lying within the counterbore and a protective end member having a shank portion extending through the central sleeve portion and into the opening concentric with the counterbore, said shank portion having a knurled portion adjacent the protective end member and extending within the sleeve portion in the counterbore and interlocked with the material of said sleeve portion.

10. Connection means for securing a protective end member having a shank portion inwardly of the end of a shuttle, said connection means comprising outer and inner substantially concentric sleeve portions joined adjacent one end thereof by an integral web portion and having their opposed ends provided with surfaces which are bevelled toward each other in the direction of the web and along lines intersecting each other intermediate said sleeve portions with said shank portion being adapted to extend through the inner sleeve portion and into the material of the shuttle, said shank portion having a knurled portion adjacent the protective end of a diameter greater than the diameter of the bore of the inner sleeve portion adapted to cut into and interlock therewith when the parts are being positioned in assembled relation with the shuttle.

11. Means for connecting a protective end member to a shuttle, said means comprising an outer and an inner sleeve portion in substantially concentric relation and joined adjacent one end thereof by an integral web portion and having oppositely angled bevels adjacent their opposed ends, said inner sleeve portion being of a length greater than the outer sleeve portion, with the bevel on the outer sleeve portion extending in an outward direction and the bevel on the inner sleeve portion extending in an inward direction.
